United States Patent Office.

JOHN B. JOHNSON, OF LAUREL, INDIANA.

Letters Patent No. 78,902, dated January 28, 1868.

IMPROVED CAR-COUPING.

The Schedule referred to in these Letters Patent and making part of the same.

TO ALL WHOM IT MAY CONCERN:

Be it known that I, JOHN B. JOHNSON, of Laurel, in the county of Franklin, and State of Indiana, have invented an Improvement in Automatic Car-Couplings; and I do hereby declare that the following is a full, clear, and exact description of the same, reference being had to the annexed drawings, making part of this specification, in which—

Figure 1 is a perspective view, and

Figure 2 is a vertical section.

The same letters are employed in both figures in the indication of the same parts.

This improvement relates to a coupling by which railroad-cars may be automatically connected, and consists in a novel combination of parts, as set forth in the following description and claims:

In the annexed drawings, A is the draw-bar, with a chambered draw-head to receive the coupling-link. A spring, formed from a strip of elastic sheet metal, is bolted to the upper part of the draw-head; and being curved downwards, rests loosely at the other end upon the bottom of the draw-head. It has a hole through it at the proper point for the introduction of the coupling-pin C which passes through the draw-head. D is a pin which, resting upon the top of the spring B, near to its lower end, projects through a hole in the top of the draw-head. The lever E is attached to the top of the draw-head, and projecting laterally, rests upon the upper end of the pin D. This lever is attached, by a chain or cord, E', to a wheel, F, at or near the periphery. This wheel turns freely upon its axis, and is also connected with the coupling-pin by a cord or chain, C'. Another cord or chain, G, attached to the periphery of the wheel, is carried to the top of the car.

The operation of the coupling is as follows: The weight of the lever E must be more than sufficient to counterbalance that of the coupling-pin, the chains connecting the two with the wheel being attached on the opposite sides thereof. When the link is not inserted, the spring B rests upon the bottom of the draw-head, and the pin D is depressed, so as to allow the lever to descend and hold suspended the coupling-pin. When the link enters the draw-head passing under the spring B, it forces it upwards, and with it the pin D, and also the lever E, which is supported upon the pin D. The weight of the lever being thus taken from the wheel F, it will turn upon its axis by the weight of the coupling-pin suspended on the opposite side, and the pin will fall through the link and the lower hole in the draw-head. The weight of the lever pressing upon the spring will assist its tension in holding the link, which must be elongated on the ends, in a horizontal position, and in the right direction to enter another draw-head in coupling a train of cars. The cars may be uncoupled from the top by drawing upon the chain G, to lift the coupling-pin out of the link.

It is sometimes desirable that cars pushed together should not be coupled automatically. This is provided for by either hooking up the chain G, and holding the pin suspended, or by lifting the pin out of the draw-head by hand.

What I claim as my invention, and desire to secure by Letters Patent, is—

1. The combination of the spring B, pin D, lever E, and wheel F, and chains E' and C', with the pin and link of a railroad-car, substantially as set forth.
2. Suspending the coupling-pin C from a wheel, on the opposite side of which is a lever suspended, so as to more than counterbalance the weight of the pin, when said lever is so supported that, by the entrance of the link into the draw-head, the pin, released from the weight of the lever, will fall by its own gravity, substantially as set forth.

In testimony whereof, I have signed my name to this specification in the presence of two subscribing witnesses.

JOHN B. JOHNSON.
